UNITED STATES PATENT OFFICE.

WENDELL LOGG, OF LOS ANGELES, CALIFORNIA, ASSIGNOR TO INDEPENDENT LOCK COMPANY, OF FITCHBURG, MASSACHUSETTS, A CORPORATION.

KEYHOLE LOCK.

Application filed March 9, 1927. Serial No. 173,867.

This invention relates to improvements in keyhole locks, and more particularly to locks of the type shown and described in Patent Number 1,554,443, issued to me on September 5 22, 1925.

Among the objects of my invention is to provide a plug, or, stoppel, which is key controlled, for insertion in the keyhole of a lock whereby to prevent unauthorized access to the 10 lock.

A further object is to provide a construction of keyhole lock which may serve for locks having relative wide range of dimensions.

15 And a still further object is to provide a keyhole plug, or stoppel, which will be automatically locked against withdrawal upon insertion in a keyhole; which is so designed as to be employed in locks wherein the spacing of the walls of the lock casings varies, even to the extent of including a portion of 20 the length of the catch of the plug, and to provide a construction which is simple and economical and lends itself to multiple or 25 quantity production.

My improvements consist in the novel construction, arrangement and combination of parts as hereinafter fully, clearly and concisely described, definitely pointed out in 30 my claims and illustrated by the accompanying drawing (1 sheet) in which—

Fig. 1 is a side elevation of a keyhole lock, constructed in accordance with my invention with the locking catch thereof in locking position so that the device may not be withdrawn from a door and lock therefor, without a proper key, fragments only of the door and door lock are shown and which are in section.

40 Fig. 2 is a transverse section, taken on the line 2—2 of Fig. 1.

Fig. 3 is a transverse sectional elevation taken on the line 3—3 of Fig. 1, showing the locking catch within the keyhole of the casing of the door lock and in locked position.

45 Fig. 4 is a view similar to Fig. 3, showing the catch as turned in the keyhole of the lock casing.

Fig. 5 is a longitudinal sectional elevation 50 showing the catch in locking position.

Fig. 6 is a transverse section taken on the line 6—6 of Fig. 5, showing the securing means between the stem and cylinder.

55 Fig. 7 is a view similar to Fig. 1, showing the lock partially broken away and in section,

and showing the catch as turned, by a key, to released position.

Fig. 8 is a plan view of the stem portion of my keyhole lock.

Referring more specifically to the drawing 60 A designates generally a door, which as is common, has a lock mortise 10 from which lead openings 11—11 extending from opposite sides of the mortise through the door; and B designates an ordinary door lock having the 65 usual casing side-walls 12—12 in each of which is a keyhole slot 13, registering with the openings 11 in the door.

The device of my invention embodies an 70 element C constructed as a unit and consisting of a cylinder 14, a stem 15, and a collar 16 formed between the cylinder and stem. The cylinder has a longitudinal key-slot 17 and tumbler pockets 18 formed wholly to one side of the collar 16, and the stem is formed as a 75 tube with a cavity 18' which is intersected by opposed aligned slots 19—19', through which slots is extended a catch 20 arranged in the cavity and pivoted on a pin 21. The catch 20 is formed on one end with a cam 80 face 22 extending vertically adjacent to the pivotal support of the catch on the pin 21, and the body of the catch 20 extending from the side of the pivot pin 21 opposite the cam 22 is formed with parallel upper and lower 85 margins *a* and *b* providing the catch with a major length having a dimension substantially equal to the diameter of the stem 15 so that when the catch is moved to a position 90 substantially parallel with the stem its major length projecting from the pin will lie bodily within the stem as shown by dotted lines in Fig. 5; the outer end portion of the catch being extended on the under side thereof beyond the uppermost slot 19 in the stem to provide a motion limiting shoulder 23. A wall 95 portion *c* is formed on the outer end of the catch extending beneath the shoulder 23 and from the margin *b*, the lower edge of which wall portion normally lies within the slot 19'. 100

This wall portion will be projected through the slot 19' when the catch 20 is disposed in its depressed position as indicated by dotted lines in Fig. 5. By this arrangement the catch will be guided in the opposed slots 19 and 19' irrespective of its position around the pivot 21, as both the upper portion of the catch and the lower wall portion thereof will at all times extend within the confines of the slots 19 and 19'. It will be observed how- 105 110

ever that when the catch is disposed in its depressed position as shown in dotted lines in Fig. 4, the major portion of its length represented by its margins *a* and *b* will lie wholly within the stem 15 and that when the catch is depressed either wholly or partially the lower portion of the catch contiguous to the pin 21 will not project beneath the stem 15. This construction of the catch 20 is important and advantageous in that it permits the use of the device in a door lock in which the side walls 12 of the lock are so close together that when the device is positioned in the keyhole the inner end portion of the catch will extend into the lock opening 13 as shown in Fig. 1, as will later be described. Within the cavity 18' is a yielding pressure means consisting of a bearing or ball 24 which seats against the cam 22, a spring 25, and a bearing 26 preferably in the form of a ball, which is secured in the cavity as by crimping the end of the tubular stem to form a retaining shoulder as shown at 27.

The spring 25 acts through the ball 24 on the cam face 22 to normally dispose the catch 20 in an outermost position with the shoulder 23 abutting against the wall of the cylinder 15 at the end of the slot 19 so that the outer portion of the catch 20 will project from the cylinder 15 in the locking position as shown in Fig. 5.

A cylindrical casing 28 formed with a radially extending tumbler housing 29 is extended telescopically over the cylinder 14 to cover the tumbler pockets 18 and afford a housing in which the cylinder 14 is turnable. The housing 29 is formed with a plurality of bores 32 in each of which is placed a tumbler 33, a follower 34, and a spring 35 which bores are closed after assemblage of the parts therein by plugs 36 driven into the outer ends of the bores in frictional engagement therewith. Extending rearwardly from the tumbler housing 29 is a web 37 which projects beneath the cylinder 15 and is adapted to be extended into the keyhole opening 13 in one of the walls of the lock casing. The upper edge of the web is formed with a lug 38 projecting alongside a transverse notch 39. In assembling the device the cylinder 14 is inserted in the bore of the casing 28 from the rear end of the latter with the lug 38 positioned in the slot 17 which slot extends through the collar 16 as particularly shown in Fig. 8. The lug 38 may be thus brought to a position past the collar 16 so that the latter will extend into the notch 39 whereupon burrs 40 are formed on the margins of the slot 17 where the latter passes through the collar 16 as shown in Fig. 6, so as to inhibit withdrawal of the lug 38 through the slot. The collar 16 then being positioned in the notch 39 the cylinder 14 and casing 28 will be held against longitudinal movement relatively to each other with the cylinder 14 turnable in the casing. This man-

ner of assembling the cylinder within the casing is advantageous in that it obviates the use of extraneous securing devices and enables interconnection of the cylinder and casing with great facility.

In the operation of the invention, after first locking the door lock in the usual manner with its key and withdrawing the key, the stem 15 is inserted in the keyhole together with the casing 28 and tumbler housing 29; the stem 15 being passed through the door lock casing such distance as to permit the catch 20 to snap into place behind the first wall of the casing as particularly shown in Fig. 1. The casing 28 and tumbler housing 29 will then fill the keyhole so as to prevent insertion of keys or other instruments into the door lock. The device will then be securely held in the keyhole against turning and against removal.

To effect removal of the device, a proper key 41 is inserted in the key slot 17 to bring the tumblers 33 to their unlocking position as is common in tumbler locks whereupon the cylinder 14 may be turned to dispose the catch 20 in a downwardly extending position as shown in Fig. 7 so that it may be withdrawn through the keyhole.

In event the side walls 12 of the door lock casing are disposed in such close proximity that when my device is placed in its locking position within the keyhole, the catch 20 will extend into the keyhole opening 13 as shown in Figs. 1 and 3 no obstruction to rotation of the stem 15 will be afforded by reason of depression of the catch as might then occur, as the lower edge of the catch will remain within the boundaries of the stem 15 as shown in Fig. 4. This is of material advantage over any construction in which depression of the catch would cause the lower portion thereof to extend into the parallel sided portion *d* of the keyhole opening 13, as should this occur turning of the stem 15 to an unlocking position would be inhibited, thereby preventing withdrawal of the device from the key-hole by operation of the key 41.

I claim:

1. In a lock of the class described, a catch whose major length portion comprises substantially parallel sides, a cam formed at one end of said major portion and a motion limiting shoulder opposite said cam and offset from said major length portion.

2. In a device of the class described, an element forming a stoppel for the key hole of a lock, a key controlled stem rotatably carried by said element, a spring actuated latch pivotally carried by the stem for normal projection radially therefrom and whose major length portion may be swung to a position wholly within the stem.

3. A device of the class described comprising a keyhole stoppel consisting of a substantially cylindrical portion and a radially ex-

tending web said web having a plurality of bores formed therein to receive lock tumblers, a lock cylinder rotatably mounted in said stoppel, a stem extending from the lock cylinder, a spring actuated catch carried by the stem, a collar between said cylinder and stem, there being a key slot formed in said cylinder and through said collar, a portion of said web

being extended through the slot in said collar and said collar being burred to prevent movement of the said web portion axially relative to the stem. 10

In testimony whereof, I have affixed my signature.

WENDELL LOGG.
